UNITED STATES PATENT OFFICE.

ALEX A. CLARKE, OF DALLAS, TEXAS.

SURFACE-TREATING TOOL.

1,407,381.

Specification of Letters Patent. Patented Feb. 21, 1922.

Application filed November 23, 1920. Serial No. 426,098.

To all whom it may concern:

Be it known that I, ALEX A. CLARKE, a citizen of the United States, residing at Dallas, in the county of Dallas and State of Texas, have invented certain new and useful Improvements in Surface-Treating Tools, of which the following is a specification.

This invention relates to new and useful improvements in surface treating tools.

10 The invention has particularly to do with that type of surface treating tools, in which a supporting frame, is provided with a motor propelled surface treating drum arcuately adjustable in said support.

15 The object of the invention is to provide a tool in which the surface treating drum is advanced to the work or retracted therefrom by arcuately adjusting the same.

20 An apparatus designed to carry out the invention will be hereinafter described together with other features of the invention.

The invention will be more readily understood from a reading of the following specification and by reference to the accompanying drawings, in which an example of the invention is shown, and wherein:

Fig. 1 is a side elevation of a tool constructed in accordance with my invention,

25 Fig. 2 is a plan view of the same, a portion being illustrated in section,

Fig. 3 is a sectional detail on the line 3—3 of Fig. 2, and

Fig. 4 is a vertical sectional view on the line 4—4 of Fig. 3.

35 In the drawings the numeral 10 designates an elongated frame having a flat base and side flanges 11 merged into a transverse central housing 12. The housing has a cover 13 fastened therein by machine screws 14. Upright handles 15 are provided at each end of the frame. The base of the frame has a central transverse slot 16.

40 At each end of the housing, a trunnion 17 extends inwardly. A transverse cradle 18 has at each end, a hub 19 receiving the trunnion at that end. The cradle is arcuate in cross-section, conforming to the general shape of the housing and its ends are flat. At the center of each end of the housing, an angular socket 20 is provided. The sockets are below the hubs at which the cradle is pivoted.

45 A revolving drum 21 is mounted in the cradle. The drum contains the elements of an ordinary electric motor and is mounted to revolve on an armature 22 which has at

each end, an angular stud 23 filling in the socket 20 thereat. By this means the armature is held against rotation and the drum is supported in the housing. The motor may have a suitable source of electrical connection and other details which it is not considered necessary to illustrate. The drum 21 has a covering or sleeve 24 of sand paper, felt or other abrading or polishing material, secured thereto in a suitable manner. The drum depends through the slot 16 and the frame is moved longitudinally by means of the handles.

The essential feature of the invention is the adjustment of the drum. It will be seen that the drum is journaled in the cradle 18 below the pivots of the latter and by swinging the cradle, the drum is raised or lowered. For swinging the cradle a worm-gear segment 25 is fastened to one of the hubs 19 and is engaged by a worm screw 26. The worm screw is fastened on a shaft 27 which has its inner end supported in a bearing bracket 28 on the end of the housing. This shaft extends through a bearing collar 29 mounted in the side of the housing 12 and carries a bevel gear 30 on its outer end. The gear 30 meshes with a bevel gear 31 on the outer end of a transverse counter-shaft 32, supported in standards 33 raising the base of the frame.

A bevel gear 34 on the inner end of the counter-shaft meshes with a bevel gear 35 on the forward end of a central longitudinal adjusting shaft 36 which is supported in an upright standard 37. A thumb wheel 38 is mounted on the outer end of the shaft 36 in close relation to the adjacent handle 15. The operator while grasping the handle may turn the wheel with his thumb and fingers. It will be seen that the shafts are rotated by turning the wheel 38, whereby the screw 26 is revolved. The screw revolves the segment 25, whereby the cradle is swung. The segment may be revolved in either direction from the central position indicated in Fig. 4, and the drum raised by being swung arcuately. Then by reversing the rotation of the wheel 38 and thus revolving the segment in the opposite direction, the drum is lowered as is obvious.

In using the tool the operator grasps the handles 15 and starts the motor so as to revolve the drum 21. By turning the thumb wheel 38 the screw 26 is caused to revolve through the agency of the parts 27, 30, 31, 32,

34, 35 and 36. It will be seen that the screw revolves the segment 25 and this swings the cradle 18, whereby the drum is arcuately adjusted, thus being raised and lowered 5 through the slot 16. If the drum is cutting too deep, the operator has merely to turn the wheel 38 and swing the cradle, whereby the drum is raised. A minute adjustment may be had and may be effected while the 10 machine is in operation.

Various constructions may be used for adjusting the drum and the invention is presented as including all such modifications as properly come within the scope of the ap- 15 pended claim.

What I claim, is:

In a surface treating tool, an elongated frame having a lower face adapted to slid- 20 ably contact with the surface to be treated and to be manually shifted over such surface, handles arranged above the frame and se- cured to the ends thereof, a transverse hous-

ing formed upon the central portion of the frame, said frame being provided beneath 25 the housing with a transverse opening, trunnions secured to the housing at its ends and projecting inwardly, a cradle having open- 30 ings in its ends to pivotally receive said trunnions, the ends of the cradle extending down- wardly below the trunnions, a rotatable sur- face treating drum connected with the lower portions of the ends of the cradle at points beneath said trunnions, a worm segment rigidly secured to the cradle and arranged 35 between one end thereof and the end of the housing, a shaft extending longitudinally of the frame and arranged between the end of the cradle and the end of said housing and having a worm engaging the worm segment, an element arranged adjacent one handle to 40 be manually operated, and operating means between the element and the shaft.

In testimony whereof I affix my signature.
ALEX A. CLARKE.
